SHOE CLEANING AND POLISHING MACHINE

Mathew Hillard Thornton, St. Paul, Minn.

Application February 1, 1934, Serial No. 709,314

21 Claims. (Cl. 15—35)

This invention relates to a shoe shining machine and while the machine might be variously controlled, it is preferably arranged to operate automatically in response to the deposit of a coin. Such a machine is very desirable in places and at times where the facilities of a modern shoe shining parlor are not available.

It is an object of this invention to provide a shoe shining machine of simple and compact construction and which is constructed and arranged to clean and polish the various parts of shoes of different sizes.

It is another object of the invention to provide a machine having a rotatable shoe engaging means such as a brush and means for moving said brush about a shoe in a path determined by the engagement of said brush with the shoe together with means for rotating said brush as it is moved about the shoe.

It is also an object of the invention to provide a machine comprising a series of brushes movable about the shoe for performing different operations thereon, said brushes being moved in a path determined by their engagement with the shoe together with means for rotating said brushes as they are moved about the shoe.

It is another object of the invention to provide a machine having a rotatable member movable about a vertical axis passing through a shoe support on which the shoe is placed, said rotatable member carrying a series of circumferentially spaced and swingingly mounted means for operating on the shoe arranged to be carried about the sides of the shoe in a path determined by their engagement with the shoe in the rotation of said member.

It is also an object of the invention to provide a shoe shining machine in which a brush is moved about the shoe and rotated while being so moved, said brush also being moved vertically to engage different parts of the shoe.

It is a further object of the invention to provide a shoe shining machine having polishing means which move around the shoe together with a spraying means movable around the shoe, said spraying means being operated by positively moving liquid thereto and by supplying air thereto.

It is also an object of the invention to provide a shoe shining machine having means for polishing the toe of the shoe including a revolvable carrier and a spraying means mounted on said carrier, said spraying means being operated at certain times to spray liquid on the toe of the shoe and having air supplied thereto at certain times.

It is still another object of the invention to provide a shoe shining machine having a series of means for operating on the shoe movable successively about the sides of the shoe together with means for spraying liquids upon the shoe and means for controlling the spraying of said liquids so that they are sprayed only at desired times.

These and other objects and advantages of the invention will be fully set forth in the following description made in connection with the accompanying drawings, in which like reference characters refer to similar parts throughout the several views and in which:

Fig. 1 is a central vertical section;

Fig. 2 is a transverse vertical section taken substantially on line 2—2 of Fig. 1 as indicated by the arrows;

Fig. 3 is a horizontal section taken substantially on line 3—3 of Fig. 1 as indicated by the arrows;

Fig. 4 is a vertical section taken on line 4—4 of Fig. 1 as indicated by the arrows;

Fig. 5 is a partial plan view of certain parts;

Fig. 6 is a plan view of the machine, some parts being broken away;

Fig. 7 is a vertical section taken substantially on line 7—7 of Fig. 6 as indicated by the arrows;

Fig. 8 is a vertical section taken substantially on line 8—8 of Fig. 1 as indicated by the arrows;

Fig. 9 is a horizontal section taken substantially on line 9—9 of Fig. 8 as indicated by the arrows;

Fig. 10 is a vertical section taken substantially on line 10—10 of Fig. 2 as indicated by the arrows;

Fig. 11 is a vertical section taken on line 11—11 of Fig. 10 as indicated by the arrows;

Fig. 12 is a vertical section taken on line 12—12 of Fig. 10 as indicated by the arrows;

Fig. 13 is a section taken on line 13—13 of Fig. 10 as indicated by the arrows;

Fig. 14 is a top plan view of one of the liquid spraying devices used, some parts being broken away;

Fig. 15 is a plan view of certain parts, partly in horizontal cross section;

Fig. 16 is a view in elevation as seen from the left of Fig. 15, some parts being broken away and others shown in vertical section;

Fig. 17 is a vertical section taken on line 17—17 of Fig. 15 as indicated by the arrows;

Fig. 18 is a top plan view of a coin deposit and control mechanism, some parts being broken away and others shown in horizontal cross section;

Fig. 19 is a vertical section taken on line 19—19 of Fig. 18 as indicated by the arrows;

- Fig. 20 is a partial view showing the coin operating mechanism;
- Fig. 21 is a vertical section on line 21—21 of Fig. 18 as indicated by the arrows;
- 5 Fig. 22 is a view similar to Fig. 19 showing the parts in different positions;
- Fig. 23 is a partial view similar to Fig. 18 showing the parts in different positions;
- 10 Fig. 24 is a view similar to Fig. 23 showing the parts in still different positions;
- Fig. 25 is a partial plan view of a guiding mechanism;
- 15 Fig. 26 is a front elevation of the parts in Fig. 25;
- Fig. 27 is a vertical section taken substantially on line 27—27 of Fig. 8 as indicated by the arrows and shown on an enlarged scale;
- 20 Fig. 28 is a view in side elevation, partly in vertical section of part of the structure shown in Fig. 14;
- Fig. 29 is a view in side elevation of a polishing brush;
- Fig. 30 is a fragmentary view in side elevation, the casing being shown in vertical section; and
- 25 Fig. 31 is a partial vertical section taken substantially on line 31—31 of Fig. 6 as indicated by the arrow.
- Referring to the drawings, a machine is shown comprising a base member or plate 30 from which upstands a rear wall or plate 31 and on which is superposed a top plate 32. A front plate 33 extends downward some distance from and beneath plate 32 and a semi-cylindrical plate or casing 34 extends beneath and downward from the sides 35 of top plate 33. Side plates 35 extend forwardly in vertical planes from rear plate 31 and a semi-cylindrical casing 36 extends forwardly quite a distance from side plates 35 at a height such as shown in Fig. 1, the same being of greater width than the rear plate 31. A plate 37 of general annular shape overlies the top of casing 36 and extends inwardly to front plate 33 and a plate 38 forming the front of casing 34 is curved at its lower end to extend horizontally over the top of plate 37 and to overlie an opening 37a therein. Plate 38 at its horizontal portion also has an opening 38a therein. Side plates 35 are connected at their bottoms to base 30 by angle brackets 30a.
- A stationary post 40 is threaded into the top of the base plate 30 substantially centrally thereof transversely and forwardly of the middle point thereof longitudinally. A sleeve 41 is journaled on post 40, the lower portion of said sleeve having formed thereon or secured thereto a pulley 42. The upper end of sleeve 41 has formed thereon a gear 43. A rotatable member or turntable 44 has a central hub journaled on the sleeve 41 and the lower end of said hub has formed thereon or secured thereto a gear 45. Gear 45 meshes with another gear 46 having formed thereon or secured thereto a sprocket 47, which sprocket has running thereover and is driven by a chain 48 in turn running over a sprocket 49. Gear 46 and sprocket 47 are journaled on a stud 46a secured in base member 30. The sprocket 49 is secured to the lower end of a shaft 50 journaled in bearings 51a formed on a frame member 51 secured to rear plate 31. Shaft 50 is driven by a beveled gear 52 secured thereto which meshes with and is driven by a beveled gear 53 secured to a shaft 54 journaled in portions 51b of the frame 51. Beveled gear 53 has secured thereto a sprocket 55 which is driven by chain 56 running thereover, said chain also running over a sprocket 57 secured to a shaft 58. Shaft 58 is journaled in a swinging frame 59 mounted to swing on shaft 54, said frame having arms 59a extending to shaft 58. The turntable 44 has studs 60 secured therein at each side of post 40 on which are journaled gears 61 disposed about and meshing with gear 43. There are four gears 61 spaced equally circumferentially about the axis of gear 43. The gears 61 have formed thereon or secured thereto at their upper ends pulleys 62. A top plate 63 extends over the tops of pulleys 62, studs 60 passing through said plate and said plate being engaged by the heads of said studs. Plate 63 has a hub surrounding post 40 and a plate 64 is secured to the top of post 40 by the screws 65 and extends over the hub of plate 63. Plate 64 is shown in transverse cross section in Fig. 4 and shown in side elevation in Fig. 1. It will be seen from the latter figure that said plate has the general form of the bottom of a shoe having an offset portion 65a adapted to receive the heel of the shoe which is to be shined. The front vertical portion of the heel of the shoe can be placed against the vertical portion of plate 65 which connects the front portion thereof to the portion 65a. Member 44 is shown as having outwardly extending arms 44a which are four in number and equally spaced circumferentially and these arms have passing therethrough vertical studs 66, the lower ends of which are threaded into one end of arms 67. Double pulleys 68 are journaled on studs 66 above arms 44a and each of said pulleys is overlaid by a washer 69 on stud 66. A pin 70 extends through each stud 66 above washer 69. Each arm 67 has secured therein a stud 71 and the hub 72a of a brush 72 is journaled on each of said studs 71. Belts 73 extend around and between pulleys 62 and 68 respectively and belts 74 extend around and between pulleys 68 and the hubs 72a. Brushes 72 are thus driven from pulley 42 through gears 43 and 61 and the pulleys 62 and 68. The arms 67 are each urged to swing inwardly by torsion springs 75 engaging the same and extending about studs 71 and secured to the under side of arms 44a as shown in Fig. 5, these springs not being shown in the other figures for the sake of clearness. The studs 71 have bores in their upper ends receiving the compression springs 76. These springs bear at their upper ends on plates 72b secured to the upper ends of hub 72a, which plates have central recesses therein receiving a ball 77, which ball engages a substantially annular cam plate 78 secured to brackets 79 which are in turn secured to the front wall 36. Plate 78 has a central opening therein through which the shoe is placed when the same is to be shined. Pulley 42 is driven by belt 80 extending thereover and over a pulley 81 secured to the lower end of a shaft 82. Shaft 82 is journaled in bearings 51c of frame 51 and has secured to its upper end a beveled gear 83. Beveled gear 83 is driven by another beveled gear 84 secured to a shaft 85 extending horizontally and journaled in bearings 51d of frame 51 and having secured at one end a pulley 86 having a hub secured to said shaft by any suitable means such as the set screw 87. Pulley 86 is a double pulley having the smaller pulley 86a forming a part thereof. Pulley 86 is driven by a belt (not shown) running over the same and a pulley 88 secured to the motor shaft 89 of a motor 90 carried on a shelf 91 secured to the casing walls 35 and 31.
- Each stud 71 in the arms 67 has secured to its lower end a roller 92 which is arranged to engage

at times with a cam track 93 or a cam track 94. Cam tracks 93 and 94 are connected and supported by V-shaped clips 93d supported on small brackets 94d secured to base plate 30. Cam track 5 93 is of semi-circular shape at its rear end and has parallel portions extending forwardly, one of which terminates in the front end 93a as shown in Fig. 3 and Fig. 25. The other side terminates in a curved portion 93b, the end of which is spaced 10 forwardly from the end of portion 93a. The outer cam track 94 has a semi-circular end portion at its rear end and has parallel side portions extending forwardly, one of which terminates in a slightly inturned portion 94a and the other one 15 of which terminates in a slightly inwardly extending portion 94b. A spring plate 95 of curved form is secured to the end portion 94b and extends some distance therefrom as shown in Fig. 25. A vertically movable cam section 96 is provided having a curved portion 96a which is tapered to extend close to the end portion 93b. Cam 20 96 has its other end 96b substantially aligned with end portion 94a. Portions 96a and 96b are connected by a very thin vertical web. Cam 96 is 25 carried on the front end of a lever comprising spaced arms 97 which have downwardly inclined portions 97a adjacent their front ends and which then extend rearwardly in an opening in bottom plate 30. Arms 97 have holes therein extending 30 over pins 98 projecting upwardly from a plate or bar 99 extending transversely in said opening in bottom plate 30. Arms 97 are thus fulcrumed on plate 99 and extend rearwardly and have at their rear ends upturned portions 97b secured to 35 an upstanding plate 100 having a stud 101 in its upper end on which is journaled a cam roller 102 engaging with a cam 103 secured to a rotatable cam plate 104 journaled on a stud 105 secured in the rear portion of frame 51. Stud 40 105 has thereon a collar 106 and said collar and plate 104 are held thereon by a pin 107 passing through said stud. Plate 104 has secured thereto a sprocket 108 and a chain 109 runs over sprocket 108 and over another sprocket 110 journaled on 45 a stud 111 also secured in the rear portion of frame 51. Chain 109 engages with one side of a sprocket 112 secured to shaft 58. Shaft 58 is driven as previously explained and chain 109 is thus driven by sprocket 112 and said chain rotates sprocket 108 and cam plate 104. The plate 100 has a pin 113 projecting rearwardly therefrom to which is attached one end of a tensile spring 114, the other end of which is secured to a pin 115 projecting forwardly from a fixed portion 55 of the frame. Spring 114 acts to hold cam roller 102 against cam 103 and to hold the movable cam section 96 in depressed position. Shaft 58 has thereon a cam roller 120 which engages the upper side of cam 104 and shaft 58 has a clip 60 121 secured thereto and a tensile coiled spring 122 is secured to the lower side of this clip and has its other end secured to a pin 123 secured to a portion of frame 51. Clip 121 is in the form of a plate overlying the top of shaft 58 having 65 projecting ears through which extend the ends of a yoke or clevis 121a (see Fig. 10) having threaded thereon the nuts 121b which engage the top of plate 121. Spring 122 holds the roller 120 in engagement with cam 104. The reel 140 is 70 as stated carried on shaft 58 and this reel and the brushes thereon are thus pulled downwardly by spring 122 and raised by the cam 104. One brush 72g is a polishing brush and is made of felt or other fabric while the other brushes 72 are bristle brushes. Brush 72g preferably is rotated 75

at much higher speed than the other brushes 72 and for this purpose its hub 72a will be somewhat smaller and the pulley on stud 66 over which belt 74 runs will be somewhat larger than the other pulleys over which the belts 74 run. 5

A reel 140 is provided having arms 140a from which project spindles 141, each of which carries a rotating brush 142. Brushes 142 have hubs 142a journaled on spindle 141 and said brushes have pulleys 142b adapted to come into contact with a belt 143 to be driven thereby. Brushes 142 are held on spindles 141 by cotter pins 141a. The central part of reel 140 is formed as a reservoir 140b to be further more fully described. Reel 140 is carried on the front end of shaft 58, which shaft as already described is movable with and carried in swinging frame 59. Shaft 58 has secured thereto a worm wheel gear 144 which is driven by a worm gear 145 secured to shaft 82, shaft 82 thus furnishing the drive for shaft 58. 20 A horizontal shaft 146 is provided journaled in bearings 51e on frame 51, which shaft has secured thereto a pulley 147 driven by a belt (not shown) running thereover and over pulley 86a. Shaft 146 has secured thereto a beveled gear 148 25 meshing with a beveled gear 149 on a shaft 150. Shaft 150 has secured thereto a pulley 151 over which runs the belt 143, said belt also running over a pulley 152 journaled on a stud 153 carried in a depending arm 51f on frame 51 as shown 30 in Fig. 1.

As the turntable 44 revolves the arms 67 and brushes 72 are carried about the shoe and controlled in their positions by cam 94 and the shoe. The machine also operates to spray cleaning 35 and blacking or polishing fluid on the shoe and for this purpose spraying devices are provided. Two of the arms 44a have guideways 44b thereon at one side as shown in Figs 14 to 17, which guideways have channels at their tops and bottoms adapted to receive a substantially T-shaped guide 156. Each guide member has a depending portion with a horizontal projection 156a and the same has an upwardly extending portion and a horizontally disposed portion 156b which carries or has secured thereto a liquid receiving receptacle 155 or 157. Receptacles 155 and 157 have filling openings closed by threaded and slotted plugs 155a and 157a. The members 156 are slideable inwardly and outwardly on guide portion 44b and are constantly urged inwardly by tensile coiled springs 158. One receptacle 157 has at its upper end a small casing 159 having a chamber therein and liquid is supplied to this chamber by a tube 160 which communicates at its lower end with the lower end of a cylinder 161 secured to receptacle 157 or member 156. Cylinder 161 is in communication with receptacle 157 through a small passage 157b. Cylinder 161 has a piston 162 which is reciprocable therein and has secured thereto a rod 163. Rod 163 extends through an arm 164a of a member 164 and nuts 165 are secured to said rod above and below said arm. Member 164 has a cylindrical portion through which passes a cylindrical rod 166 having formed thereon a double thread 166a. The thread 166a has one portion or thread thereof right handed and the other portion or thread thereon left handed. 65 Member 164 acts as a nut and for this purpose a screw 167 extends through a boss thereon and has a tapered end portion extending into the groove of the threads 166a. Rod 166 extends through a bearing 156c carried by member 156 70 75

and collars 168 are secured to rod 166 at the top and bottom of bearing 156c. Said collars may be secured in any suitable manner as by the set screws 169. Rod 166 has secured to its lower end a gear 170 which meshes with another gear 171 journaled on a headed stud 172 which is threaded into and carried by portion 156c of member 156. Gear 171 meshes with a rack 173 which is secured to the outer side of cam track 94 and is continuous about said cam. It may be stated that the rollers 92 engage the cam 94 above rack 173. Air is also used to spray the liquid from casing 159 and air is supplied to said casing by a conduit 174 which extends to a member 175 connected to and communicating with the chamber in casing 159. Chamber 159 has a small spray orifice 159a leading therefrom and directed toward the shoe. The conduit 174 is connected at its other end to a nipple 176 secured in the side of plate 63 and passages 63a lead inwardly in plate 63 and communicate at their inner sides with grooves 40a formed in post 40. Passages 40b lead downwardly through post 40 from the annular passages 40a and communicate at their lower ends with another annular passage 40c. Tubes 177 are secured to nipple connections 177a secured in plate 99. Passages 99a lead from nipples 177a and communicate with the annular passage 40c in post 40.

Receptacle 155 does not have a force feed. Said casing has a portion 155b at its top having a passage therethrough from which leads downward a tube 155c having a contracted portion at its upper end with an opening therethrough and having its lower end open and disposed adjacent the bottom of casing 155. Casing 155 has a small casing 155d at its upper end having a chamber therein communicating with the top of receptacle 155 and conduit 174 communicates with the chamber and portion 155d. Conduit 174 communicates at its other end as already described, with the nipple 166 in plate 63 so that air is supplied through said conduit. Member 156 carrying receptacle 155 has a stud 155g secured therein and a gear 155e is secured to said stud and is adapted to travel about and mesh with the rack 173. The passage through portion 155b extends from the top of receptacle 155 over the top of tube 155c and downwardly at one side of said portion. It will be seen that air will pass into the top of receptacle 155 and out through said passage over the top of tube 155c and will draw liquid through said tube and spray the same as indicated in Fig. 28.

Tubes 177 lead to and are connected to elbow connections 178 which in turn are secured to a member 179. Member 179 is supported on plates 179a secured to rear wall 31 and has disposed in vertical cylindrical passages therein plungers 180 which have journaled in their upper ends cam rollers 181, which cam rollers engage the periphery of a cam 182 secured to cam plate 104. Plungers 180 are urged upwardly by springs 183 secured at their upper ends to pins 184 and at their lower ends to pins 185, which pins 185 are secured to plungers 180 respectively. Pins 185 project rearwardly through slots in member 179. Member 179 has a horizontal passage 179b therein communicating with the passages through which plungers 180 extend and said plungers have reduced portions 180a adapted to align with passage 179b in certain posi-

tions of said plungers. A nipple 186 is secured in the bottom of member 179 and has a passage communicating with passage 179a. A conduit 187 is connected to nipple 186 and this conduit extends upwardly along the rear wall 31 to an air pump 188, which pump is supported on a bracket 189 secured to the shelf or plate 91. Pump 188 has a pulley 190 thereon which is driven by a belt 191 running thereover and over a pulley 192 secured to shaft 85.

Spraying devices are also carried by the reel 140 to spray cleaning and polishing or blacking fluid on the toe of the shoe. For this purpose the reel 140 is provided at its central portion with a casing 140b. Said reel also has secured thereto at circumferentially spaced points the casings 194, which casings have reduced portions on which are threaded the nozzle members 195. Each member 194 is bored to have slidable therein a plunger 196 in the outer end of which is journaled a cam roller 197. Cam roller 197 is adapted to engage in the revolution of reel 140 with a cam 198 secured to a bracket 199 mounted on the portion of frame 51 from which depend the bearings 51e and 51f. Member 194 has a reduced portion beyond its threaded portion forming an annular chamber in nozzle 195 and spaced endwise from member 195 and a conduit 200 communicates with this annular chamber and with a passage 201 in shaft 58. There is another passage 202 in shaft 58 similar to passage 201 and the same communicates with another conduit 203 similar to conduit 200 which communicates with the other nozzle member 195 which as shown in Fig. 11 is spaced 90 degrees from the nozzle with which conduit 200 communicates. Plunger 196 has a reduced portion forming a piston which slides in a reduced cylindrical portion 194a of member 194. Said piston has a rod 196a extending therefrom which extends through a central aperture in the end of nozzle member 195 and has a beveled headed portion 196b thereon adapted to at times act as a valve to close the aperture in the end of nozzle 195. The plunger 196 has a pin 204 extending therethrough and projecting at either side through the ends of which extend headed pins 205 which also extend through pins 206 extending outward at either side of nozzle member 195. Compression coiled springs 207 surround pins 205 and have their ends engaging respectively pin 204 and pins 206. These springs normally tend to move plunger 196 out of nozzle member 195 and said plunger is pushed inward by engagement of roller 197 with cam 198. The cylindrical bore of member 194 in which plunger 196 moves has communicating therewith a conduit 208 which also communicates with the chamber in casing 140b. The cylindrical bore or chamber in the other member 194 has a similar conduit (not shown) which communicates with a chamber in casing 140b. Casing 140b has a central longitudinal partition 140c dividing the chamber therein into two compartments. These compartments have filling openings extending through bosses on casing 140b, which openings are closed by plugs 140d having knurled heads. Conduit 208 thus communicates with one of these compartments and the other conduit similar thereto which communicates with the other spraying nozzle 195 communicates with the other compartment. The bar or bracket 199 has secured thereto brackets 209 having vertical parallel portions each of which has formed therein a cam slot 209a shown in Figs. 1 and 10 and a 75

collar 210 slidable longitudinally on shaft 58 has projecting pins 210a extending into the cam slots 209a respectively. Collar 210 has a flat side engaging one side of one bracket 209 to prevent any turning movement. It will be seen that when the reel 140 is raised and lowered by cam 104 and spring 122 that collar 210 will be moved longitudinally of shaft 58. Collar 210 has an annular chamber 210b therein surrounding shaft 58 which at times is moved into alignment with the ends of passages 201 and 202 which terminate in the periphery of shaft 58. A nipple 211 is secured in collar 210 and communicates with annular passage 210b and said nipple has secured thereto a conduit 212 which extends to a T member 212a in conduit 187 and thus communicates with said conduit.

The machine is coin-controlled and motor 90 is controlled by a switch contained in a casing 220. Said switch comprises contact members 221 and 222 to which conductors 223 of the motor circuit are respectively connected. Said switch also has a movable contact member 224 pivoted on pivot 225. A throw lever 226 swings about the axis of pivot 225 and has a lower pointed end engaging a spring 227 which is secured to the bottom of casing 220. Spring 227 has an angle shaped portion beneath lever 226 and tends to snap said lever and contact member 224 into open or closed position after the same have been moved a certain distance. An operating bar 228 is provided for lever 226 and has a slot 228a in which the upper rounded end of said lever is disposed. Bar 228 is supported on a plate 229 supported by casing 220. Bar 228 at one end has a cutaway portion 228b so that one end is quite narrow or of small thickness. Bar 228 also moves in contact with a plate 230 disposed in a vertical plane at its rear side and also in engagement with a plate 231 at its forward side. A coin slot 232a is provided in a plate 232 secured to top plate 90 and a bar 233 of the same thickness as bar 228 and longitudinally alined therewith has a cutout portion 233a which is normally disposed beneath the slot 232. A spring 234 is secured to the rear of plate 230 and has an end portion 234a extending through a slot 230a in plate 230. Bar 233 has a pin 235 secured therein and projecting forwardly therefrom to which one end of a tensile coiled spring 236 is connected, the other end of said spring being connected to one of the side walls 35. Pin 235 projects through and moves in a slot 231a in the plate 231. Plates 230 and 231 extend to plate 229 on which bar 233 also moves. Plate 229 has a slot 229a therein through which a coin is adapted to drop into a suitable coin box 214. Another slot 229b is provided in plate 229 vertically alined with slot 232a but too small to permit a five cent piece or a nickel to drop therethrough but small enough to permit the passage of a one cent piece. Pin 235 is engaged by a bar 237 having a cutout portion provided with a shoulder 237a from which an inclined surface 237b extends to the end of bar 237. Bar 237 has a cam plate 238 secured to its rear side adapted to engage and be lifted by a projection 220a on the end of switch casing 220. Bar 237 is pivotally connected at one end by stud 239 to one end of a link 240 which is secured to a crank shaft 241. Shaft 241 is journaled in the front and rear walls 31 and 33 and has secured thereto adjacent the front wall a lever 242. A screw 241a is threaded into shaft 241 and has a head engaging front wall 33. Lever 242 extends through the top plate 32 and has a handle 242a at its upper end. Lever 242 has a stud 243 secured therein which passes through and pivots in a bar 244. Bar 244 has a slot 244a at one end through which passes a stud 244b secured in front wall 33. Bar 244 is pivoted on stud 244b and a tensile coiled spring 245 is secured to one end thereof and to front wall 33 below the same so that said spring normally pulls down on one end of bar 244. Lever 242 has a pin 246 projecting forwardly at its lower end beneath cover 34 which extends into a slot in a lever 247, which lever is pivoted on a stud 248 secured in front plate 38. Lever 247 extends upwardly along front wall 38 and then horizontally beneath plate 34 and has a downturned end in which the slot is provided for pin 246. Links 249 each have one end pivotally secured to lever 247 respectively above and below stud 248 and the other ends of these links are pivotally connected to levers 250 which are pivoted at their upper ends to studs 251 secured in front plate 38 and have 20 horizontal projecting portions beneath plate 37. These horizontally projecting portions are respectively secured to vertically spaced plates 252. These vertically spaced plates have openings cut therein oppositely disposed and forming a substantially elliptical opening. A layer 253 of yielding fabric such as felt or moss rubber is secured between each pair of plates 252 and these layers of fabric extend beyond the edges of plates 252 at the openings therein and have cutaway 30 portions oppositely disposed and cooperating to form a substantially elliptical opening 253a. A bar 254 is disposed immediately in the rear of sprocket 110 and guided in a bracket 255 secured to rear wall 31. Bar 254 is pivotally supported 35 at its other end by a bar 256 having a slot 256a intermediate its ends through which passes a stud 257 secured in the rear wall 31. Bar 256 has its upper end bent forwardly and extending across the plane of bar 228. Bar 254 has a recess 254a 40 therein forming a vertical shoulder 254b. Sprocket 110 has a pin 261 which projects from the rear of the sprocket in position to engage bar 254 and move into recess 254a. Bar 256 has a spring 262 secured to its upper end, the other end of which is secured to a pin 265 secured in and projecting from a plate 263 secured to rear wall 31 and in which stud 257 is secured. A stop plate 264 is secured to the rear wall 31 and has one end bent outwardly at a right angle and adapted to 45 be engaged by the upper end of bar 256 when the latter is pulled to the left as shown in Fig. 8 by spring 262.

In operation, the machine is normally in position with the parts disposed as shown in Fig. 3 55 and the lever 242 is in the position shown in dotted lines in Fig. 8. Cleaning fluid is disposed in the chamber in casing 155 shown at the left of Fig. 3 and blacking or polishing fluid is disposed in the chamber in casing 157 at the top of Fig. 3. Cleaning fluid is also disposed in one compartment in casing 140b and this is in communication with the nozzle 195 shown at the left of the reel in Fig. 2 while blacking or polishing fluid is disposed in the other compartment in casing 140b 60 and this is in communication with the nozzle 195 shown at the top of the reel in Fig. 2. The patron desiring to have his shoes shined places his foot in the opening 253a disposing his shoe on plate 65 65 as shown in Fig. 1 and deposits a nickel in the coin slot 232a. Following directions which will be printed on the machine the patron now takes hold of handle 242a, swings the same to the right as shown in Fig. 8 as far as it will go and then swings it back to the left as far as it will go, thus 70 75

giving the handle one complete reciprocation. Spring 245 and bar 244 act to hold lever 242 at one end or the other of its reciprocation as pivot 243 moves to one side or the other of pivot 241a. 5 As the lever 242 was moved to the right as described bar 237 was moved to the right as shown in Fig. 19 by link 240 and shaft 241 and shoulder 237a engaged over pin 235. When the coin was deposited in slot 232a it dropped down onto plate 10 229 and into the recess or cutaway portion in bar 233. If a smaller coin had been deposited it would have dropped through the slot 229b and not be in position to work the machine. When lever 242 is 15 swung back to the left bar 237 is moved to the left and pin 235 is moved to the left by shoulder 237a. This moves bar 233 to the left and the coin 20 260 is moved to the left on plate 229 and engages the end of bar 228 moving the same to the left thus swinging lever 226 and closing the switch 25 in casing 220. The coin 260 in moving to the left moves past spring portion 234a swinging the latter rearwardly and moving partially past the end of said spring portion. When the bar 233 moves so that its end moves past the coin spring 234 30 moves the coin forwardly so that it now moves into the cutaway portion or recess 228b, of bar 228. The coin 260 is now aligned longitudinally with the end of bar 233.

When the switch in casing 220 is closed motor 35 90 is started and turntable 44 begins to revolve. This rotation is caused by gear 46 turning gear 45, gear 46 being turned by sprocket 47 which is in turn driven by chain 48 running over sprocket 49 secured to shaft 50. Shaft 50 is driven by beveled 40 gears 52 and 54 in turn driven through chain 56 running over sprocket 57 on shaft 58. Shaft 58 is driven by worm wheel gear 144 driven by worm gear 145 on shaft 82, which shaft is driven through gears 83 and 84, the latter being secured 45 to shaft 85 driven by pulley 86 in turn driven from motor pulley 88. At the same time the brushes 72 are rotated. This rotation is caused by pulley 42 turning gear 43, the latter driving the four gears 61 which are secured to the pulleys 62.

50 Pulleys 62, drive pulleys 68, through the belts 73 and pulleys 68, drive the brushes through the belts 74. As turntable 44 rotates and brushes 72 are rotated reel 140 is also rotated by shaft 58. Cam plate 104 is also rotated through chain 109. The first operation on the shoe is to clean the same with a rotating brush. The cleaning brush is indicated as 72d in Fig. 3. As this is carried around in a counter-clockwise direction its roller 92 as 55 shown in Fig. 3 is in engagement with cam track 94. As the roller reaches portion 94b it follows said portion inwardly and bearing against the flexible spring 95 pushes said spring in to the position shown in dotted lines in Fig. 25 and into alinement with the movable cam section 96b.

60 This cam section is at this time lowered since roller 92 has moved off of cam 103 permitting spring 114 to lift the rear end of bars 97 and lower the movable cam section. Roller 92 on stud 71 of the brushing roller 72d therefore swings inwardly with its arm 67 toward the cam track section 93a and starts on its movement around cam 93. As arm 67 swings inwardly, brush 72d 65 is brought into engagement with the side of the shoe and travels around the shoe in contact therewith, being revolved at the same time, and brushes any dust or dirt from the shoe. Rollers 92 do not normally engage cam track 93, but arms 67 are limited by brushes 72 engaging the shoe. Only if a very small shoe or no shoe is present will 70 75 rollers 92 engage track 93. Track 93 forms a

safety feature to prevent collision and damage to the brushes should the machine be run with no shoe therein. As turntable 44 continues to turn, spraying casing 155 on one of the arms 44a following brush 72d, travels around the shoe having its gear 155e in mesh with rack 173. Cam 182 is in engagement with rollers 181 and plungers 180 are moved downwardly so that the portions 180a are alined with passage 179b and air is admitted from tube 187 into passage 179b. This air is supplied from the air pump 188 which is now being driven from pulley 192 through belt 191 and pulley 190 and which starts when motor 89 starts. Air is thus supplied through tubes 177 to post 49 and the passages 40c and passes to the casing 155d through the conduit 174. As member 44 rotates gear 155e is carried around rack 173 acting as a cam. Air is delivered into the top of container 155 placing pressure upon the cleaning liquid in said container and liquid is forced up through the tube 155c. Air also passes out through the passage in casing 155b and passes over the top of tube 155c acting to divide the liquid and spray it as indicated in Fig. 28. The passage of the air over the top of tube 155c also acts to draw the liquid up in said tube, the same acting as in the well known structure of atomizer. The cleaning liquid is thus sprayed on the shoe as receptacle 155 moves about the shoe.

The next brush designated 72e in Fig. 3 has now traveled along the side of cam track 94 and it in turn reaches portion 94b and its roller 92 swings inwardly along spring 95 and moves inwardly toward track portion 93a, to bring brush 72e in engagement with the shoe. The spring 95 cushions the movement of the rollers 92 as they move inwardly. The arms 67 are, of course, swung inwardly when permitted to do so by rollers 92 by the springs 15. The brush 72e now is carried around the shoe in engagement therewith as its arm 67 is controlled by said brush engaging the shoe and this brush cleans any dirt not removed by brush 72d. The cleaning fluid loosens some dust and dirt and the shoe is in effect washed clean by the cleaning fluid and brush 72e. The other casing 157 follows portion 72e and the blacking or polishing fluid is now sprayed upon the shoe. As gear 171 is carried about rack 173 it is rotated and rotates gear 170 and shaft 166 having thereon the double reverse screw 166a. This screw acting through the nut portion 164 raises said portion and with it plunger rod 163 and piston 162. As the casing 157 moves about the shoe in one revolution when the brush 72f is in engagement with the shoe, piston 162 is being depressed and the blacking or polishing liquid is positively forced through conduit 169 into the chamber in casing 159 and since as above stated air is delivered to said chamber, the liquid and said air pass out in a jet through orifice 159a and liquid is sprayed on the shoe. It will be seen that there is a positive spraying of the liquid due to piston 162 and there is thus no chance of the liquid sticking or drying in the discharge passages as might be the case if air alone were used for the spraying force. The shoe is thus sprayed with the blacking or polishing liquid. The casing 157 is now followed by the third brush designated 72f in Fig. 3 and this brush brushes the shoe on which the blacking has been sprayed. This brush acts to rough polish the shoe so that it is in condition for final polishing. The polishing brush designated 72g now reaches the portion 94b of cam track 94 and as above described its arm 67 swings in as its 75

roller 92 moves over spring 95 and inwardly toward cam portion 93a. This brush thus travels about the shoe and as before described this brush is driven at very high speed considerably faster than the other brushes and is made of polishing material such as felt, piled fabric or other good polishing fabric. The sides of the shoe are given a high polish by this brush. This brush is preferably made of the shape shown in Fig. 29. This shape has a top portion 12f of greater diameter than the lower part of the brush adapted to reach up some distance on the shoe. As brush 12g moved inwardly into engagement with the shoe the first brush 12d moved along adjacent the portion 93b. At this time cam 103 again engages roller 102 and plate 100 and the rear end of bars 97 are depressed. This oscillates bars 97 and raises the movable cam section 96 so that section 96b is raised and now extends on a level with portions 93b and 94a. As brush 12d therefore moves around portion 93b it is guided by portion 96b outwardly to portion 94a and its roller will now follow cam track 94 around the shoe until it again comes around to cam track portion 93b. As the various brushes 12 move around the shoe they are maintained in an elevated position with the balls 77 against plate 78. As shown in Fig. 1 plate 78 is higher at its front end which is over the rear part of the shoe and the brushes can move upwardly so as to be sure to engage the full height of the heel or the box of the heel. As the brushes move around the front of the shoe they are depressed by plate 78 as it is not necessary to have them so high at the toe part of the shoe and it is desired to depress them so that they will not interfere with the toe brushes carried on reel 140 which move across the toe as will be later described.

From the above description it will be seen that the various brushes 12, namely, cleaning brush 12d, wet cleaning brush 12e, blacking brush 12f and polishing brush 12g each move around the shoe once in contact with the shoe with their rollers adjacent the cam track 93 and they move around the shoe once with their rollers in contact with cam track 94. When the rollers 92 are in contact with the cam track 94 the brushes are held in position out of contact with the shoe. It will be noted that cam 102 is only in engagement with rollers 101 through somewhat less than one-half revolution of cam 104 as clearly shown in Fig. 8, and this half revolution occurs while the brushes 12 are moving about the shoe and in engagement therewith. It is desirable to discontinue the spraying a short time before the brushes pass out of engagement with the shoe so that no liquid will be sprayed on the polished or finished portion of the shoe or on a portion which will not be gone over by the polishing brush. At this time also the piston 162 is being moved downward by screw 166a. While the brushes 12 are moving around the shoe out of engagement therewith screw 166a will elevate the piston 162 and liquid from tank or receptacle 167 can flow through passage 157b beneath piston 162 into cylinder 161. There is thus no spraying of the liquid and there is no air discharged through orifice 159a while the brushes are moving around the shoe out of contact therewith as cam 102 is out of contact with rollers 101. It will also be seen that cam plate 104 makes one revolution while turntable 44 is making two revolutions.

The brushes 142 are provided for brushing the top of the toe of the shoe. There are four of these brushes and they are like brushes 12 for first brushing the shoe, then wet cleaning the shoe, then blacking or rough polishing the shoe and then polishing the shoe. These brushes 142 move across the toe in alternate succession with the brushes 12, that is the toe cleaning brush moves across the toe just after the cleaning brush 12d moves around the toe, the wet cleaning brush 142 moves across the toe just after the wet cleaning brush 12e moves around the toe, the blacking or rough polishing brush 142 moves across the toe just after the blacking or rough polishing brush 12f moves around the toe and the final polishing brush 142 moves across the toe just after the final polishing brush 12g moves around the toe. As above stated reel 140 is rotated by shaft 58, which as already explained, is driven by chain 56. In Fig. 2 the brush 142 shown at the lower left hand corner of reel 140 is the cleaning brush and after 20 this passes downwardly the spraying nozzle 195 passes downwardly over the toe and roller 197 engages cam 198 so that plunger 196 is moved inwardly in member 194. Cleaning fluid passes from the cleaning fluid compartment in casting 140b into member 194 and as plunger 196 is moved inwardly this cleaning fluid is positively forced outwardly through the nozzle aperture. It will be seen that as soon as plunger 196 has made a small movement the aperture in conduit 30 206 is covered or cut off so that the fluid must be forced out through the nozzle aperture. As each brush 142 approaches its lowest position of revolution, reel 140 is in its lowest position, being pulled downwardly by spring 122 and roller 120 35 is in one of the low portions of cam plate 104. As the brushes come into their lowest position pulleys 142b engage the upper run of belt 143 and are thus driven at high speed. As previously described belt 143 is driven through shaft 150, gears 40 148 and 149, pulley 147 and pulley 86a which is on shaft 85 driven through pulleys 88 and 86 by motor 90. As each brush 142 approaches its low position, roller 120 moves on to a low portion of cam 104 and frame 59 is pulled down by spring 45 122 and collar 210 is moved rearwardly on shaft 58 due to the action of projecting pins 210a in the slots 209a. As the first nozzle 195 shown at the left of Fig. 2 moves downwardly to be over the toe of the shoe and roller 197 engages cam 198 as 50 above described, collar 210 is in its forward position and air is delivered through conduit 212 into the annular spaces 210b through passage 201 and conduit 200 into the annular chamber in nozzle 195 and this air rushes out through the 55 nozzle orifice and sprays the liquid being forced out through said orifice by plunger 196. The cleaning fluid is thus sprayed on top of the toe of the shoe as the first nozzle 195 passes thereover and this is done before the wet cleaning brush 142 shown at the upper left hand corner of the reel 140 in Fig. 2 passes over the toe. When roller 197 travels past cam 198, plunger 196 is moved outwardly by the springs 207 and liquid can again flow through conduit 208 into the cylinder in 60 member 194. When roller 197 moves away from cam 198 springs 207 move valve 196b into closed position closing the nozzle orifice and preventing any dripping of liquid. After this wet cleaning brush passes over the toe the second nozzle 195 65 comes into position over the toe and its roller 197 engages cam 198 and blacking is sprayed on the toe of the shoe just as is the cleaning fluid above described. At this time collar 210 is in its forward position so that air is delivered through 70 75

passage 202 to the nozzle 195 shown at the top of the reel 140 in Fig. 2. The reel 140 is raised between the passage of each brush 142 over the toe of the shoe and brushes 142 thus entirely clear 5 the brushes 12 passing around the sides of the toe portion of the shoe. It will be understood that one of the brushes 142 is a polishing brush and this is shown at the lower right hand corner in Fig. 2. This brush will be constructed of felt, piled fabric 10 or other suitable fabric as is the polishing brush 72g. This polishing brush 142 will preferably be a little farther from the center of reel 140 as shown in Fig. 11. Said polishing brush is provided with a smaller pulley 142b than the other brushes 142 15 so as to be driven at higher speed. In practice it was found that after the blacking and rough polishing brush 72f had passed around the shoe and the corresponding toe brush 142 had passed over the shoe, that a line would be visible on the shoe. 20 It was for this reason that the polishing brush 72g as shown in Fig. 29 was made. This brush has the upper portion 72j, which as shown in Fig. 29, reaches up quite a distance on the shoe and this portion in polishing the shoe entirely removes 25 the line above mentioned. As the brush passes around the heel of the shoe the portion 72j merely folds upwardly to a greater degree than shown in Fig. 29.

The machine goes through a complete cycle for 30 each shoe and the machine is constructed and arranged so that it will go through two complete cycles when one coin is deposited. It has already been stated that when the customer deposits the coin in slot 232a that he swings handle 242a and lever 242 to the right as shown in Figs. 6 and 8 and then back to its left hand position shown in said figures. When lever 242 is in its left hand position as shown in Figs. 6 and 7, it will be seen that the upper end of lever 247 is moved to 40 the right as seen in Fig. 7 and links 249 move the lower ends of levers 250 together thus moving inwardly the fabric layers 253. These fabric layers move in and tightly grip the ankle or foot of the customer just above the top of the shoe and these insure that no cleaning fluid or blacking fluid will be sprayed on the hose of the customer. As above described when the coin 260 is deposited bar 233 is moved to the left by bar 237 and the coin pushes on the end of switch operating bar 50 228 and throws the switch to closed position starting the machine in operation. The machine continues to operate as described until all of the brushes 12 have passed around the shoe in engagement therewith. As above stated the brushes 55 72 move around the shoe twice in one cycle, once controlled by cam track 94 at which time they are out of engagement with the shoe, and once controlled by being in engagement with the shoe. When the polishing brush 72g has passed around the shoe and has been guided out by movable cam section 96, the machine is again brought to rest with the brushes substantially in the positions shown in Fig. 3. Sprocket 110 makes one revolution in one cycle of the machine and as the 60 machine nears the end of its cycle pin 261 is moving upwardly as shown by the arrows in Fig. 20 and engages bar 254. Bar 254 is lifted, thus lifting lever 256 into the dotted line position shown in Fig. 20 and moving its end into the line of movement of bar 228. Pin 261 moves into recess 254a and against shoulder 254b and swings lever 256 moving its upper end to the right as shown in Fig. 20, pushing bar 228 to the right and again throwing the switch in casing 220 so that the 70 switch is moved to open position. When bar 256 75

has its upper end moving to the right as shown in Fig. 20 to move bar 228 to the right and throw the switch, the switch snaps to the right due to spring 227 and bar 228 is given an impulse to the right. This moves its left hand end out of engagement with bar 256 and said bar drops to the full line position shown in Fig. 20 before the machine comes to rest. Bar 256 is thus out of the way of bar 228 when the machine is again to be started. The machine has been built and operates without any trouble. The Patent Office drawings were made from the actual machine. Motor 90 now stops and the machine comes to rest. As above described when coin 260 moved past the end 234a of spring 234 said end engaged the coin and pushed it forwardly and moved it into the recess 228b. The patron now again moves lever 242 to the right and then moves it back again to the left. When it is moved to the right, shoulder 237a on bar 237 again engages pin 235 and when the lever is moved to the left bar 233 is again moved to the left as shown in Figs. 18, 19, and 22 to 24. As bar 233 moves to the left its end pushes coin 260 to the left and said coin pushes on the shoulder on bar 228 and moves bar 228 to the left. When bar 228 is moved to the left it again moves lever 226 and closes the switch in casing 220 again starting the machine in operation. When coin 260 has moved bar 228 to the left said coin moves over opening 229a and drops through said opening into coin box 214. When bar 237 moves a certain distance to the left cam 238 rides up over projection 220a raising bar 237, moving shoulder 237a above pin 235, releasing said pin and permitting spring 236 to move 35 bar 233 to the right to its normal position. The machine now goes through another cycle as already described, and polishes the other shoe. It will be seen that if lever 242 is moved without any coin being deposited bar 233 will be moved 40 to the left by bar 237 as shown in Figs. 18 and 19 but will not move bar 228 so that the switch will not be thrown and the machine will not operate. Lever 242 will merely swing idly without starting the machine. 45

The screw 166a as stated has reverse threads and these are of different pitch. In practice this screw has been made with four threads to move nut 164 upwardly and eight threads to move nut 164 downwardly. Nut 164 and piston 162 are thus 50 raised more quickly than they are lowered. Some time and motion are lost in the nut moving from one thread to another and piston 162 must move past opening 157b. It is desired to have pressure spraying during the period that the receptacle is 55 moving about the shoe and while brush 72f is in engagement therewith. This is accomplished by the above stated difference in the threads. The piston 162 is moved downward after passing opening 157b to the end of its downward movement 60 while container 157 is making one passage around the shoe, and said nut 164 is switched from one thread to another at bottom and top, moved upwardly and downwardly far enough for piston to pass opening 157b in the other passage of container 157 about the shoe. In said latter passage brush 72f is out of engagement with the shoe. Positive pressure spraying is thus had during one 65 revolution of container 157.

From the above description it will be seen that 70 applicant has produced a very efficient shoe shining machine and one that will operate entirely automatically after it has been started by the deposit of a coin and the movement of the operating lever. All parts of the shoe are not 75

only cleaned but all parts have polish applied thereto and are effectively polished by the polishing brushes. As stated the hose of the patron are well protected from being discolored or 5 damaged in any way. It will be obvious that either brown or black shoe polish may be placed in the container 151 and in one of the compartments in casing 140b. The machine has been 10 amply demonstrated in actual practice and found to work very successfully.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

What is claimed is:—

20 1. A shoe shining machine having in combination, a series of rotatable members for engaging the shoe and cleaning and polishing the same, a cam track extending substantially about said shoe, means for moving said members about 25 the shoe out of engagement therewith and controlled by said cam track and for moving said members about the shoe in engagement therewith uncontrolled by said cam track.

2. The structure set forth in claim 1 and a second cam track for limiting the movement of said members inwardly or toward said shoe.

3. A shoe shining machine having in combination, a series of rotatable members for engaging the shoe and cleaning and polishing the same, means for moving said members successively about a shoe out of engagement with said shoe and successively about said shoe in engagement with said shoe.

4. A shoe shining machine having in combination, a shoe support, a rotatable member, means for rotating said member, a series of spaced shoe polishing means swingably mounted on said member, a pair of guide tracks extending about said support and means for causing said means to move in one rotation of said member under control of one of said tracks and in another rotation of said member in engagement with the shoe but limited by another of said tracks.

5. A shoe shining machine having in combination, a shoe support, a plurality of spaced means for operating on a shoe movable successively about the sides of said shoe, a member carrying a plurality of spaced means for operating on said shoe revoluble about a horizontal axis for movement across the toe of said shoe in alternate relation respectively to said first mentioned means and means for moving said members and last mentioned means upwardly as said first mentioned means successively pass around the toe 60 of said shoe.

6. A shoe shining machine having in combination, a support adapted to be engaged by the shoe, a member rotatable about a vertical axis extending through said support, a plurality of circumferentially spaced swinging members on said member, shoe engaging means carried by said swinging members, a pair of guide tracks extending about said support, means carried by said shoe engaging means engaging said tracks to control the position of said shoe engaging means, a spraying means comprising a cylinder, a piston movable therein, a rack on one of said guide tracks and a gear engaging said rack for moving said piston to positively spray liquid.

75 7. A shoe shining machine having in combina-

tion, a support adapted to be engaged by the shoe, a member rotatable about a vertical axis, a plurality of swingable brushes carried by said member, a pair of guide tracks for controlling the positions of said brushes, said brushes having means moving about one track with said brushes out of engagement with the shoe and adjacent the other track in engagement with the shoe and a movable cam section for causing said brushes to pass from control of one track 10 to adjacent or under control of the other.

8. A shoe shining machine having in combination, a support adapted to be engaged by the shoe, a member rotatable about a horizontal axis above said shoe, a plurality of circumferentially spaced brushes carried by said member for operating on the top of the toe of the shoe and movable thereover, circumferentially spaced spraying means carried by said member in advance of certain of said brushes, said spraying means including a piston and cylinder and means engaged by said piston in the rotation of said member for moving said piston in said cylinder to positively spray liquid as said spraying means passes over the top of said toe.

9. A shoe shining machine having in combination, a shoe support, a member rotatable about a vertical axis, a spray means carried by said member and movable in a closed path around the shoe in the rotation of said member, said spraying means comprising a cylinder, a piston movable in said cylinder for positively forcing liquid from said cylinder for spraying on said shoe and gear means operated by the movement of said spraying means in said path for moving said piston in said cylinder as said spraying means moves around said shoe.

10. The structure set forth in claim 9, an air supply means and means for connecting said air supply means and spraying means while said liquid is being forced from said cylinder.

11. A shoe shining machine comprising a brush adapted to be moved around the sides of a shoe and to be rotated when so moved having a cylindrical portion of one diameter adapted to engage the sides of said shoe and having another cylindrical portion of a greater diameter adapted to extend partially over the top of said shoe at certain parts of the shoe.

12. A shoe shining machine having in combination, a support adapted to be engaged by a shoe, a rotatable carrier above said support, a brush mounted on said carrier, means for rotating said carrier to move said brush across the toe of said shoe, a liquid-containing member movable with said carrier, a discharge means for liquid, means for positively moving liquid to said discharge means as the latter passes over said shoe, means for discharging air adjacent said discharge means, an air supply means and means for connecting said air supply means to said air discharge means when said discharge means moves over said shoe to spray said liquid on said shoe and for disconnecting said means when said discharge means is not over said shoe.

13. A shoe shining machine having in combination, a support upon which a shoe may be placed, a rotatable carrier above said support, a brush carried by said carrier and movable over the toe of said shoe in the rotation of said carrier, a spraying means rotatable with said carrier over the toe of said shoe and means for operating said spraying means as it moves over the toe of said shoe ahead of said brush and for dis-

continuing the operation thereof when it is not over the toe of said shoe.

14. A shoe shining machine having in combination, a support adapted to be engaged by the shoe, a member rotatable about a horizontal axis above said support, a plurality of circumferentially spaced brushes carried by said member and successively moved in a continuous movement to and over the toe of said shoe in the rotation of said member for operating on the top of said shoe during said movement and spraying means carried by said member for spraying liquid upon said toe in advance of certain of said brushes and operated by the rotative movement of said member.

15. A shoe shining machine having in combination, a support adapted to be engaged by the shoe, a member rotatable about a horizontal axis above said support, a plurality of circumferentially spaced brushes carried by said member and successively moved over the toe of said shoe in the rotation of said member to operate on the top of said shoe during said movement, said brushes being rotatable about axes substantially parallel to said axis, means for rotating said brushes as they move over the toe of said shoe and spraying means carried by said member for spraying liquid upon said toe in advance of certain of said brushes.

30. 16. A shoe shining machine having in combination, a support for a shoe, a member rotatable about a horizontal axis above said support, a spraying means carried by said member including a cylinder adapted to receive liquid, a piston in said cylinder, a nozzle communicating with said cylinder, means for operating said piston by the movement of said member in the rotation of said member to positively move said liquid to said nozzle and means for supplying air to said spraying means operated when the latter passes over said shoe.

17. A shoe shining machine having in combination, a brush, means for moving said brush around said shoe in engagement with the sides thereof, means for rotating said brush as it moves around said shoe, a resilient means constantly acting on said brush to lift the same and means engaging said brush to govern its vertical position, said means having a portion permitting lifting of said brush as it moves around the heel of said shoe.

18. A shoe shining machine having in combination, a brush, means for moving said brush around said shoe in engagement with the sides thereof, means for rotating said brush as it moves around said shoe, a spring acting on said brush to lift the same, a plate extending around said shoe engaged by the top of said brush and governing the vertical position of said brush, said plate having a raised portion around the heel of said shoe to permit lifting of said brush as it passes around said heel.

19. A shoe shining machine having in combination, a shoe support, a succession of spaced shoe treating members, the members being constructed so that different ones perform different operations on a shoe, means for revolving all of the members simultaneously around the shoe support, and means for holding the members against a shoe on the shoe support during one revolution and for spacing each of them from the shoe for one revolution after it passes a fixed point in the orbit of the members.

20. A shoe shining machine having in combination, a shoe support, a succession of spaced shoe treating members, the members being constructed so that different ones perform different operations on a shoe, means for revolving all of the members simultaneously around the shoe support, means for pressing the members towards the shoe support, guide means for spacing the members away from the shoe, and means for allowing each member to make one revolution uncontrolled by the guide means and a second revolution under the control of the guide means, the members being successively placed under the control of the guide means as they successively pass a fixed point in their common orbit.

21. In a shoe shining machine as described in claim 19, a liquid projecting means directed toward the position for the shoe and mounted to be revolved around it ahead of one of the shoe treating members by the means for revolving the shoe treating members, and means for actuating the liquid projecting means during alternate revolutions, the liquid projecting means going into and coming out of action approximately as it passes the point at which the treating members start and stop being held against the shoe.

MATHEW HILLARD THORNTON. 50.
